UNITED STATES PATENT OFFICE

2,460,953

COVER HOLDER FOR PRESSING MACHINES

Manford Spicer, Jr., Kansas City, Mo., assignor
of twenty-five per cent to George Johnson,
Kansas City, Kans.

Application November 6, 1944, Serial No. 562,146

2 Claims. (Cl. 38—66)

1

The present invention relates to new and useful improvements in devices for holding the covers on the pads of pressing machines, and the invention has for its primary object to provide means for holding the cover in position on the pad without necessitating the use of draw strings, tacks, pins or other similar fastening devices commonly used for this purpose.

A further object of the invention is to provide a cover holder of this character embodying a pair of rigid strips extending longitudinally under the pressing head of the machine, each strip having hooks adapted for engaging the edges of the cover together with flexible means extending transversely under the machine for connecting the pair of strips to each other and adapted for adjustment whereby to draw the cover tightly on the machine in a uniform manner both at a narrow and wide ends thereof.

Another object of the invention is to provide a cover holder of this character by means of which the cover may be secured easily and quickly in position and which at the same time is simple and practical in construction, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view of a pressing buck showing the cover in position thereon.

Figure 2 is a bottom plan view.

Figure 3 is an end elevational view.

Figure 4 is an enlarged detail of one of the transverse connecting members for the side strips of the cover holder and with parts broken away and shown in section, and

Figure 5 is a perspective view of the connector for one of the flexible members of the holder.

Referring now to the drawings in detail, wherein for the purpose of illustration I have disclosed a preferred embodiment of the invention, the numeral 5 designates a conventional form of pressing buck on which a pressing pad 6 is mounted.

A removable cover 7 is provided for the pad, the cover being frequently removed for replacing the same after becoming worn or soiled.

In order to secure the cover in position I provide a holder which comprises a pair of relatively thin strips 8 and 9 of wood, light weight

2

metal or other suitable material, each of the strips having a plurality of longitudinally spaced eyes 10 secured thereto and to which substantially sharpened hooks 11 are pivotally attached at one end and adapted for penetrating the material of the cover 7 adjacent the side edges thereof to secure the cover in position.

The strips 8 and 9 extend longitudinally under the pressing buck 6 adjacent each side edge thereof and to the strip 9 is attached a plurality of brackets 12 having a free edge bent into the form of a hook 13 provided with a notch 14 adapted for receiving a cord or other flexible member 15 having a knot 16 engaged behind the hook 13 to retain the cord in the notch thereof.

The other end of the cord 15 is similarly provided with a knot 17 engaged in a notch of the hooked end 18 of a connecting plate 20 to which a link 21 is attached at one end, the other end 20 of the link being pivotally mounted on a pin 22 extending transversely at one end of a connector 23.

The opposite end of the connector is provided with a screw 24 secured to the connector by means of a pin 25, the screw being threaded into a sleeve 26 having a head 27 at one end thereof, the sleeve being inserted through the strip 8 and retained therein by the head 27. The head 27 is provided with a kerf 28 adapted to receive a screwdriver to facilitate the threading of the sleeve into and out of position on the screw 24.

A handle 29 extends laterally from the connector 23 with a head 30 on its outer end and spaced from the connector to provide a finger-grip for securing the connector against movement while the sleeve 26 is threaded on the screw 24.

The flexible member 15 extends transversely 40 under the pressing buck 5 and a plurality of the transversely extending connecting members connect the strips 8 and 9 at longitudinally spaced intervals as shown to advantage in Figures 1 and 2 of the drawings and by adjusting the sleeve 26 45 on the screw 24 the strips 8 and 9 may be adjusted relative to each other at any desired point throughout their length to thus draw the edges of the cover 7 tightly on the pad 6.

The adjustment of the transverse members 50 connecting the strips 8 and 9 may thus enable the strips to be drawn close together at the outer end of the pressing buck to compensate for the variations in the width of the pressing buck at the inner and outer ends thereof.

55 When the knot 16 of the flexible member 15 is

removed from the hook 13 at one side of the holder the flexible member may then be wound around the handle 29 to prevent entanglement thereof when the holder is not in use.

It is believed that the details of construction, operation and advantages of the device will be readily understood from the foregoing without further detailed explanation.

Having thus described the invention, what I claim is:

1. In a pressing machine cover-holding device, the combination, which comprises a pad, a cover adapted for positioning over said pad, longitudinally disposed rigid strips associated with the opposite sides of said pad and cover, hooks pivotally attached to said rigid strips for removably holding the edges of said cover, flexible elements pivotally attached to the strips at one side of the pad extending under the pad, threaded sockets aligned with said flexible elements rotatably mounted in the strips on the other side of the pad, threaded studs extending from said sockets, links providing connecting means between said flexible elements and studs, means pivotally connecting the links at one end to said studs, and means pivotally connecting the other ends of said links to said flexible elements.

2. In a pressing machine cover-holding device, the combination, which comprises a pad, a cover adapted for positioning over said pad, longitudinally disposed rigid strips associated with the

opposite sides of said pad and cover, hooks pivotally attached to said rigid strips for removably holding the edges of said cover, flexible elements pivotally attached to the strips at one side of the pad extending under the pad, threaded sockets aligned with said flexible elements rotatably mounted in the strips on the other side of the pad, threaded studs extending from said sockets, links providing connecting means between said flexible elements and studs, means pivotally connecting the links at one end to said studs, and means pivotally connecting the other ends of said links to said flexible elements.
